UNITED STATES PATENT OFFICE.

JOHN A. CRUMP, OF PHILADELPHIA, PENNSYLVANIA.

CURTAIN POLE OR ROD.

1,178,994.

Specification of Letters Patent. Patented Apr. 11, 1916.

Application filed August 31, 1915. Serial No. 48,252.

To all whom it may concern:

Be it known that I, JOHN A. CRUMP, a citizen of the United States, residing at 322 East Thompson street, Philadelphia, in the 5 county of Philadelphia and State of Pennsylvania, have invented new and useful Improvements in Curtain Poles or Rods, of which the following is a specification.

The invention relates to supports for curtains and has for an object the provision of a curtain rod or pole which will effectively support the curtain or portiere in a window or doorway without necessitating the mar- 10 ring or injuring of the casing thereof.

Among other features the invention 15 contemplates a rod or pole which is adjustable in length to accommodate itself to sashes or doorways of different widths and which can be quickly applied and does not require the 20 usual sockets or other means screwed or otherwise secured in the sash or casing for the purpose of holding the rod or pole in position.

Still further embodiments of the invention 25 reside in a pole or rod that is preferably made in sections, one fitting into the other, so that the length of the pole or rod can be easily varied as desired, with suitable means arranged to prevent accidental dis- 30 engagement of the sections.

In the further disclosure of the invention use is made of the accompanying drawings, forming a part of this specification, in which similar characters of reference denote cor- 35 responding parts in all the views, and in which:

Figure 1 is a side elevation of the curtain rod, showing the manner of mounting the same, parts being broken away to disclose 40 the underlying structure; Fig. 2 is an enlarged fragmentary vertical section taken through the rod at the point of engagement of the sections; Fig. 3 is a vertical section taken on the line 3—3 in Fig. 2, and Fig. 4 45 is a perspective view of the element serving to prevent disengagement of the sections.

Referring to the views, the rod in its 50 entirety is indicated by the numeral 5 and comprises telescoping tubular sections 6, 7, each having a transverse pin 8 passing through

its inner end as shown, with an elongated loop-like element 9 arranged within the sections and passing around the pins 8, said pins passing loosely through the space 10 of the element. 55

An expandable helical spring 11 encircles the element 9 and is also arranged within the sections with the ends of the spring abutting against the pins 8, the said spring thereby tending to move the sections relatively out- 60 ward or apart while the element 9 prevents relative disengagement of the sections as mentioned heretofore.

The numeral 12 indicates the usual window casing or sides of a doorway and ar- 65 ranged in the ends of the sections to abut against the casing are friction cushions or holders 13, each providing a rubber or other friction head 15 having a curved face 16 and held on the section by a shank 17 70 threaded into the internally threaded ends 18 of the tubular sections 6 and 7.

It will now be seen that when the rod in its entirety is arranged between the sides of the casing as shown in Fig. 1, the spring 11 75 bearing against the pins 8, will tend to move the sections apart thus causing the heads 15 to bear against the sides of the casing 12. By providing the curved faces 16, the heads, when compressed by the action of the 80 spring, will cause the curved faces to almost flatten out and thus a suction will be produced greatly facilitating the holding or supporting power of the heads. The element 9, operating against the action of the 85 spring, will prevent the sections from becoming relatively separated and thus limits their relative outward movement induced by the spring 11.

From the foregoing description it will 90 therefore be seen that the article described consists of few and simple parts; can be cheaply manufactured and the parts thereof readily assembled, and that the simplicity of the article permits of the user readily applying it in such places where it is desired to use the same, without necessitating the use of tools, screws or other means of support. 95

Having described my invention, I claim: 100

A curtain rod or pole for sashes compris-

ing relatively movable sections, a pin passing through each section adjacent the inner end thereof, an elongated element engaging with the pins of each section for holding the same together, a spring embracing the elongated element and abutting at its opposite terminals with the opposed surfaces of each

of said pins, and contact heads threadedly engaged in the outer ends of each of the movable sections and adapted to frictionally engage with the sash for retaining the pole in supported position.

In testimony whereof I affix my signature.
JOHN A. CRUMP.
